AUDIO OSCILLATOR

Sam Snead, Milwaukee, Wis., assignor to The Otoflex Corporation, Milwaukee, Wis., a corporation of Wisconsin

Application October 5, 1934, Serial No. 746,988
Renewed November 4, 1937

14 Claims.

(Cl. 179—1)

This invention relates to audio oscillators for the production of audio waves having a distinctive wave form which greatly departs from the sinusoidal wave which is desired in oscillators used heretofore.

I have found that audio sounds having certain wave forms and controllable in frequency and volume are particularly useful for the treatment and alleviation of certain defects of the ear and 10 to provide an oscillator capable of producing such sound waves is an object of the present invention.

It has also been found that when stimulating hearing by a continuous sound of constant intensity and pitch, the hearing mechanism becomes 15 gradually accustomed thereto and does not respond any longer. If, on the other hand, the pitch of the sound is varied continuously within limits of audibility, the hearing is continuously stimulated. It has further been found that hearing mechanism, when impaired, frequently does not respond to a single sound stimulation. However, if such stimulation is repeated for several 20 separated intervals in succession, the summation of such stimuli results in a response resulting in perception of the sound. To provide a method of and apparatus for automatically producing such variation and repeated stimuli is another object of my invention.

30 The aforescribed stimulation is further improved by varying the pitch from one limit to the other in steps whereby the variation is temporarily reversed but so that the net result is a variation in the desired direction. Such variation is known as "pilgrim" steps wherein "ripples" are superimposed upon the main oscillatory variation, and to provide a method of and apparatus for such automatic variation in "pilgrim" steps is another object of my invention.

40 Another object is to provide an electrical oscillator producing audio waves having harmonics of relatively high amplitude.

Another object is to provide an oscillator of the aforementioned type which is easily adjustable for varying frequencies within the audible range.

Another object is to provide an oscillator, the volume of which is adjustable over a wide range without affecting the frequency for which it is 50 adjusted.

Another object is to provide an oscillator having constant wave shape for varying frequency and volume.

Another object is to provide an oscillator in 55 which the sound frequency is automatically

varied back and forth between given limits, such variations having superimposed thereon ripples during part of each of which the frequency varies oppositely to the first mentioned variation.

Another object is to provide an automatic 5 method for treating the hearing mechanism by sound waves of substantially rectangular wave shape during half cycles of one polarity and triangular wave shapes during the other cycles and varying their frequency between given limits.

Other objects and advantages will hereinafter 10 appear.

The accompanying drawing is illustrative of 15 one embodiment of my invention. In the drawing,

Figure 1 is a connection diagram of an oscillator built in accordance with my invention.

Fig. 2 is an oscillogram of the wave shape of 20 the output of the oscillator.

Fig. 3 is a curve showing the relation between 25 the setting of the dial for controlling the frequency and the frequency of the output.

Fig. 4 is a similar diagram showing the relation 30 between the setting of the frequency adjusting dial and the volume of the output.

Fig. 5 is a diagram showing the variations of 35 the sound frequency with time for one cycle of such variations, while

Fig. 6 is a drawing illustrating the mechanism 40 for automatically varying the sound frequency.

Referring to Fig. 1, the oscillator consists of a high vacuum tube 1, having a heater 1^a for heating the cathode 1^b, an anode 1^c, a control grid 1^d and a screen grid 1^e. The heater 1^a as well as the heaters of the other tubes to be described 45 subsequently may be supplied with heating energy in a well known manner from any suitable source.

A second tube 2 similar in all respects to the tube 1 has a heater 2^a, a cathode 2^b, an anode 2^c, a control grid 2^d and a screen grid 2^e. Connected in cascade with the tubes 1 and 2 in a manner to be described hereinafter is a modulator tube 3 having a heater 3^a, a cathode 3^b, an anode 3^c, a control grid 3^d, a screen grid 3^e and a second 50 screen grid 3^f. The output of the tube 3 is amplified in the tube 4 having a cathode heater 4^a, a cathode 4^b, an anode 4^c and a control grid 4^d, and the output of the tube 4 is further amplified by a tube 5 having a heater 5^a, a cathode 5^b, an anode 5^c, a control grid 5^d and a screen grid 5^e. An output transformer 6 having a primary winding 6^a and a secondary winding 6^b connects the tube 5 to a series of telephone jacks by which the energy controlled by said tube 5 is to be received. 55

The apparatus also includes an inductance 7 one end terminal of which is connected to the negative grounded terminal of a source of power supply, while the other end terminal is connected 5 through a condenser 8 and a parallel resistor 9 to the grid 1^a. An intermediate terminal of the inductance 7 is connected to the cathode 1^b.

A second inductance 10 similar to the inductance 7 has its one end terminal connected to the 10 negative terminal of the power supply aforementioned, while its other end terminal is connected to the grid 2^a in series with a condenser 11 which is in parallel with a resistor 12. Connected in parallel with the inductance 7, between the grid 1^a and the negative terminal are a fixed condenser 13 of suitable capacity and a smaller adjustable condenser 14, the purpose of which will be explained hereinafter. A fixed condenser 15 and a smaller adjustable condenser 16 are connected in parallel with the inductance 10. An impedance 17 has one terminal connected to the anode 1^c while its other terminal is connected to one terminal of a resistor 18, the other end of the latter being connected to the anode 2^c. A 25 condenser 19 is connected between the anode 1^c and the control grid 3^d and a similar condenser 20 is connected in series with the resistor 18 between the anode 2^c and the control grid 3^d. The common terminal of the condenser 20 and the 30 resistor 18 is connected through a resistor 22 to the negative line. A condenser 22 connects the cathode 3^b with the negative line and is paralleled by a resistor 22^b. An impedance 23 has one terminal connected to the anode 3^c and is paralleled by two similar condensers 24 and 25 which are connected in series and their common terminal is connected to the negative line. The other terminal of the impedance is connected to the high voltage positive supply terminal through 35 resistance 26. The common terminal of impedance 23 and resistance 26 is connected through a condenser 27 to one fixed terminal of a potentiometer resistor 28, the other fixed terminal of which is connected to the negative terminal of the power supply, while the sliding contact of said 40 potentiometer is connected to the control grid 4^a. The cathode 4^b is connected to the negative terminal of the power supply through a resistor 29 paralleled by a condenser 30.

The anode 4^c is connected to the high voltage positive terminal through resistor 31 and is also connected through a condenser 32 to the grid 5^d. The latter is connected to the negative terminal of the power supply through resistances 33 and 55 34 which are in series with each other, the resistance 34 being paralleled by a by pass condenser 35. A resistor 36 connects the cathode 5^b to the negative line and is paralleled by a by pass condenser 37. The screen grid 5^c is connected to the high voltage positive terminal of the power 60 supply while the screen grids 1^c, 2^c and 3^c are connected to an intermediate voltage positive terminal of the power supply.

The primary winding 6^a is connected between 65 the anode 5^c and the high voltage positive terminal. The secondary winding 6^b of transformer 6 has a center tap which divides it into two equal sections. Connected between each end terminal and the center tap of the secondary winding are 70 normally closed double pole telephone jacks 38 and 40, respectively which in their normal position close the circuit from said outer terminal to the center tap through impedances 39 and 41, respectively. These impedances are proportioned 75 so as to equal the impedance of the usual ear

type telephone receiver which may be employed in connection with the oscillator so that the total load on the transformer 6 is not varied if a receiver is plugged into the jack and thus substituted in the circuit for the impedance 39 or 41. 5

Referring to Fig. 6, the movable plates of condenser 16 are mounted on a rotatable shaft 50 carrying a pulley 51. A string or wire 52 is wrapped around the pulley so that it rotates the latter when it is pulled forth and back. One end 10 of the string is fastened to one end of a connecting rod 53 and the other end of the string is attached near the other end of said rod by means of a spring 54, the purpose of which is to keep the string taut. 15

The second end of the connecting rod is pivoted on a pin 55 which is mounted eccentrically on a pinion 56. The latter is rotatably mounted eccentrically on a wheel 57 which in turn is rotatably mounted on a sleeve 64 and the latter rotates about a pivot 58. A suitable motor or other driving means 60 carries on its shaft a gear 61 which meshes with the gear 57. A gear 62 is keyed to the aforesaid sleeve and engages gear 56. A second gear identical to gear 62 is keyed 25 to the aforesaid sleeve and meshes with a gear 63 fastened to the motor shaft.

As the motor is rotated the connecting rod 53 is reciprocated forth and back and thus oscillates the shaft 50 of the condenser 15 with each 30 revolution of the gear 57. Simultaneously the motion imparted to the rod 53 by the rotation of gear 57 is modified by "pilgrim" steps by virtue of the rotation of pin 55 around the center of pinion 56. 35

The wire 52 and pulley 51 may obviously be replaced by a rack and pinion drive, or a lever, fastened to the shaft 50 and hinged to the rod 53, may be substituted. Other modifications of such connection are obvious. The number of pilgrim steps per cycle may be varied by varying the gear ratios of the transmission, while the length of the pilgrim steps may be varied by varying the eccentricity of the pin 55. 40

In the operation of the device, the oscillating 45 circuit which includes tube 1 and condensers 13 and 14 is adjusted for a frequency of, for example, 200 kc. To accurately adjust for this frequency the condenser 14 is manipulated. The grid resistance 9 is of such value as to cause the 50 grid to be highly positive during part of the oscillating cycle and the cyclic voltage variation impressed upon the grid, or, the grid swing, is relatively high. The grid swing is adjusted so that during the respective half cycles of the grid voltage the tube operates on parts of the grid voltage-plate current characteristic which have greatly differing average slopes relative to each other. In other words, during that half of the cycle when the grid has a relatively low voltage the tube 55 operates on the lower bend of said characteristic, while during the other half cycle the tube operates on the steep, substantially straight portion. As a result the plate current is practically zero during the greater portion of the half cycle when the tube operates on the lower bend. Furthermore, the impedance 17 which receives the output current of the tube 1 is made of relatively low value with respect to the tube impedance in order to increase in a well known manner the ratio of the 60 effective currents passed by the tube during said respective half cycles, that is, to increase the amplitude distortions. The present arrangement, due to the non-resonant operation also produces 65 distortions between the input and output of the 70 75

tube, which results in a different amplification of the various frequency components or frequency distortion of the output voltages and currents relative to the input voltages and currents.

5 The oscillator tube 2 is caused to oscillate in a manner similar to the tube 1 by adjustment of the condenser 16 but the frequency of oscillation of tube 2 is so adjusted that it heterodynes with tube 1 so that the difference frequency is within 10 the audible range and this audio frequency may be varied by adjusting the condenser 16.

The constants of the impedance 18 and the bias of the grid 2^d are chosen in a manner similar to that aforescribed in connection with tube 1.

15 The combined output of the two oscillators 1 and 2 is impressed upon the tube 3 which is resistance coupled with the generating tubes 1 and 2. The output energy of the tube 3 is impressed upon the tube 4, the radio frequency ripples being 20 filtered out in a well known manner by the impedance 23 and the condensers 24 and 25, while the audio frequency wave is not distorted from its original shape. The tube 4 is again resistance coupled to the tube 3. The ratio between the impedance 25 put of the tube 4 and the output of the tube 3 can be controlled by adjustment of the potentiometer 28 in a well known manner.

The output of the tube 4 is further amplified by the tube 5 which is coupled with the former 30 by a resistance coupling in a well known manner, while the connection of the transformer 6 to the tube 5 also presents nothing novel. By arranging the jacks and resistors controlled thereby in the manner aforescribed, the load on the tube 5 35 is always kept constant irrespective of the number of receivers plugged in so that no variable load reacts upon the device and thereby causes reactions on the frequency of the oscillators.

In the automatic operation of the device the 40 condenser 14 is set to the desired radio frequency and the volume control potentiometer 28 is set to the desired value. Thereafter motor 60 is started so as to vary the condenser 16 through the desired range and the sound waves are caused to affect 45 the auditory nerve of the patient by connecting him to one of the telephone receivers and plugging the latter into one of the jacks 38 or 40. Thereafter the device continues to vary the sound waves as aforescribed and illustrated in 50 Fig. 5, until terminated.

By employing resistance couplings in all stages between the oscillators and the final output tube the heterodyne wave form which is produced originally by the oscillators is preserved, such 55 wave form being substantially as shown in Fig. 2. It will be noted that during the one half cycle the wave shape is almost rectangular while during the intervening half cycle the wave form is sharply peaked, such a form having proved to be 60 most particularly suited for the purpose in question. My present theory is that the effect is due to the relatively sudden impact of the sound followed by a relatively long sustained maximum pressure during substantially one half of each 65 cycle of the sound wave as clearly illustrated in Fig. 2.

Fig. 3 shows the relation between the dial setting for the condenser 16 and the frequency of the output energy. It will be noticed that there 70 exists a substantially straight line relation between the dial setting and frequencies from 1000 to 10,000 cycles, this being the fundamental frequencies which are most desired in the application of the apparatus. Inspection of Fig. 4 furthermore indicates that the output of the appa- 75

ratus within the range in which the relation between dial setting and frequency is linear remains substantially constant for all dial settings, that is, the output remains constant irrespective of the frequency, a characteristic which is highly 5 desirable and important for the use of the apparatus.

What I claim as new and desire to secure by Letters Patent is:

1. An electronic generator of sound waves comprising means for producing continuous trains of waves having a wave shape which is substantially rectangular during half cycles of one polarity and substantially triangular during the alternate half cycles, said means including two adjustable 15 radio frequency oscillating circuits, each including an electronic tube having a control grid and an anode, means to bias said grid so as to reduce discharge through said tube to substantially zero value during a substantial portion of a cycle and 20 a relatively low impedance in series with said anode, and further means to superimpose the output of one circuit upon the output of the other circuit.

2. An electronic generator of sound waves comprising means for producing continuous trains of waves having a wave shape which is substantially rectangular during half cycles of one polarity and substantially triangular during the alternate half cycles, said means including two 30 adjustable radio frequency oscillating circuits each including an electronic tube having a control grid and an anode, means to bias said grid so as to reduce discharge through said tube to substantially zero value during a substantial portion 35 of each cycle, a relatively low impedance in series with said anode, and means to vary the frequency of oscillation of at least one of said circuits, and further means to superimpose the output of one circuit upon the output of the other circuit. 40

3. An electronic generator of sound waves comprising means for producing continuous trains of waves having a wave shape which is substantially rectangular during half cycles of one polarity and substantially triangular during the alternate half cycles, said means including two 45 adjustable radio frequency oscillating circuits each including an electronic tube having a control grid and an anode, means to bias said grid so as to reduce discharge through said tube to substantially zero value during a substantial portion of each cycle, a relatively low impedance in series with said anode, and motor operated means adapted to cyclically vary the oscillating frequency of one of said oscillating circuits relative 55 to that of the other of said oscillating circuits, and further means to superimpose the output of one circuit upon the output of the other circuit, so as to produce a beat frequency equal to the desired sound frequency. 60

4. An electronic generator of sound waves, comprising means for producing continuous trains of waves having a wave shape which is substantially rectangular during half cycles of one polarity and substantially triangular during the alternate half cycles, said means including two 65 radio frequency oscillating circuits, each including an electronic tube having a control grid and an anode, means to bias said grid so as to reduce discharge through said tube to substantially zero 70 value during a substantial portion of a cycle and an external impedance in series with said anode which is low in relation to the internal impedance of said tube, an amplifier and sound output means including a third tube and means to impress the 75

- output of the oscillating circuits upon said third tube.
5. An electronic generator of sound waves comprising means for producing continuous trains of waves having a wave shape which is substantially rectangular during half cycles of one polarity and substantially triangular during the alternate half cycles, said means including two radio frequency oscillating circuits, the frequency 10 of at least one of which is adjustable and each including an electronic tube having a control grid and an anode, means to bias said grid so as to reduce discharge through said tube to substantially zero value during a substantial portion of 15 a cycle and an external impedance in series with said anode which is low in relation to the internal impedance of said tube, an amplifier and sound output means including a third tube and means to impress the output of the oscillating circuits 20 upon said third tube.
6. An electronic generator of sound waves comprising means for producing continuous trains of waves having a wave shape which is substantially rectangular during half cycles of one polarity 25 and substantially triangular during the alternate half cycles, said means including two radio frequency oscillating circuits, each including an electronic tube having a control grid and an anode, means to bias said grid so as to reduce 30 discharge through said tube to substantially zero value during a substantial portion of a cycle and an external impedance in series with said anode which is low in relation to the internal impedance of said tube, an amplifier and sound output 35 means including a third tube, means to impress the output of said oscillating circuits upon said third tube and means to vary the oscillating frequency of one of said oscillating circuits relative to that of the other of said oscillating circuits 40 so as to produce a beat frequency equal to the desired sound frequency.
7. An electronic generator of sound waves comprising means for producing continuous trains of waves having a wave shape which is substantially rectangular during half cycles of one polarity 45 and substantially triangular during the alternate half cycles, said means including two adjustable radio frequency oscillating circuits, each including an electronic tube having a control grid and 50 an anode, means to bias said grid so as to reduce discharge through said tube to substantially zero value during a substantial portion of a cycle and an external impedance in series with said anode which is low in relation to the internal impedance 55 of said tube, an amplifier and sound output means including a third tube and means to impress the output of the oscillating circuits upon said third tube.
8. An audio frequency oscillator comprising two 60 oscillating circuits, each of said circuits including a tube having a grid and an anode, means adapted to control said circuits to oscillate at radio frequency including means to impress a high positive bias on said grid and to cause reduction 65 of the output of said tube to substantially zero value during a substantial part of a cycle and further including an external plate impedance load which is low relative to the internal impedance of said tube, and an amplifying tube receiving 70 the output of said first mentioned tubes.
9. An audio frequency oscillator comprising two oscillating circuits, each of said circuits including a tube having a grid and an anode, means adapted to control said circuits to oscillate at 75 radio frequency including means to impress a

high positive bias on said grids and to cause reduction of the output of said tube to substantially zero value during a substantial part of a cycle and further including an external plate impedance load which is low relative to the internal 5 impedance of said tube, an amplifying tube receiving the output of said first mentioned tubes, and electromagnetic means to convert the electrical output of said third tube into sound waves.

10. An audio frequency oscillator comprising two oscillating circuits, each of said circuits including a tube having a grid and an anode, means adapted to control said circuits to oscillate at radio frequency including means to impress a high positive bias on said grids and to cause reduction 15 of the output of said tube to substantially zero value during a substantial part of a cycle and further including an external plate impedance load which is low relative to the internal impedance of said tube, means to vary the oscillating frequency of at least one of said circuits, and an amplifying tube receiving the output of 20 said first mentioned tubes.

11. An audio frequency oscillator comprising two oscillating circuits, each of said circuits including a tube having a grid and an anode, means adapted to control said circuits to oscillate at radio frequency including means to impress a high positive bias on said grid and to cause reduction 25 of the output of said tube to substantially zero value during a substantial part of a cycle and further including an external plate impedance load which is low relative to the internal impedance of said tube, means to vary the oscillating frequency of at least one of said circuits, 30 an amplifying tube receiving the output of said first mentioned tubes, and electrochemical means to convert the electrical output of said third tube into sound waves.

12. An audio frequency oscillator comprising two oscillating circuits, each of said circuits including a tube having a grid and an anode, means adapted to control said circuit to oscillate at radio frequency including means to impress a high positive bias on said grid and to cause reduction 45 of the output of said tube to substantially zero value during a substantial part of a cycle further including an external plate impedance load which is low relative to the internal impedance of said tube, motor operated means 50 adapted to cyclically vary the oscillating frequency of at least one of said circuits to produce a heterodyne frequency within the audible range of sound, an amplifying tube receiving the output of said first mentioned tubes, and electromagnetic means to convert the electrical output 55 of said third tube into sound waves.

13. In the production of sound waves whose pitch varies periodically between a given minimum and maximum, the steps of generating two superposed alternating voltages of frequencies above that of audible sound, periodically varying the frequency of one of said voltages to produce with the other of said voltages a beat frequency which varies between said minimum and maximum, and the further step of converting the electrical energy represented by said beat frequency into audible sound.

14. In the production of sound waves whose pitch varies periodically between a given minimum and maximum, the periodic variations having superposed thereon a second series of periodic variations of a different frequency, the steps of generating two superposed alternating 7

voltages of frequencies above that of audible sound, periodically varying the frequency of one of said voltages to produce with the other of said voltages a beat frequency which varies between said minimum and maximum, superpose upon said beat frequency another periodic variation

of a different frequency within the audible range, and converting the electrical energy represented by said modified beat frequency into audible sound.

SAM SNEAD. 5
